Alexander Porter New Virginia, Maine

Letters Patent

The Subject referred to in these Letters Patent and making part of the same containing a description in the words of the said Alexander Porter himself of his Improvement in the Threshing Machine & Cleaner for Grain.

To all whom these presents shall come, Be it known that I, Alexander Porter of New Virginia, in the County of Somerset and State of Maine former have invented a new and useful improvement in the Threshing Machine and in the Mode of Screening and Cleaning of grain connected therewith & that the following is a full and exact description thereof.

I take four posts Figs 1111. four feet high made up for a frame on which I fasten four pieces of plank about six feet long Figs 22. and the width between the side pieces to be about three feet. Fig A represents a wooden or Cast iron Cylinder in which are inserted four rows of teeth to hold grain in a bed of Cast iron with one row of teeth similar to those in the Cylinder. Fig B represents the main wheel, working into the wheel Fig C which drives the Cylinder A either with bands or with gearing & connected with the same wheel. & Fig D another wheel which drives the fan of the screening Machine. Fig E represents the apron on which is placed the grain before it is threshed. The teeth represented by Fig 11 are of cast iron wrought iron and cast with the bar or wedge into a plate, and the bar or plate is fastened onto the wooden Cylinder. The teeth are wedge formed gradually by projections at the top and in the center as represented by Fig 15. The cleaner is formed by two side pieces a, a, formed so as to be admitted within the sides of the Threshing Machine and into the sides are four or more or less slide boards b b b b with long teeth made of wood or iron on which the grain and straw after threshing are to roll.

The top Comb has teeth about two feet long and the others being about the same length project forward about six inches each beyond the other and forming a gradual descent and under these Combs is a fine sieve through which the grain passes on to a fine sieve which is

calculated to let off the grain, shake it not the grain passes through
a trough or spout on the side of the cleaner the cleaner is driven by a crank 3
is attached to the side of the necessary machine and can be made to turn
by a crooked sheep. fig 4. The machine may be driven by horse, water, hand,
or any other power. The cleaner is intended to work also with a common
threshing machine as well as in the threshing machine.

What I claim as my own invention and not previously known is the ridge form and graduated projections of the teeth on the
cleaner as formed of long teeth receding a side by one comb gradually projecting
beyond the other.
